UNITED STATES PATENT OFFICE

135,975

DESIGN FOR A BARBECUE TABLE

Norman P. Miller, West Los Angeles, Calif.

Application March 19, 1943, Serial No. 109,781

Term of patent 7 years

To all whom it may concern:

Be it known that I, Norman P. Miller, a citizen of the United States of America, residing at West Los Angeles, in the county of Los Angeles, State of California, have invented a new, original, and ornamental Design for a Barbecue Table, of which the following is a specification, reference being had to the accompanying drawing, forming a part thereof.

Fig. 1 is a side elevational view of a barbecue table, showing my new design;

Fig. 2 is a top plan view;

Fig. 3 is a rear elevational view; and

Fig. 4 is a perspective view thereof.

I claim:

The ornamental design for a barbecue table, as shown.

NORMAN P. MILLER.
